(57) CLAIM

I claim the ornamental design for the headphone hanger, as shown and described.

DESCRIPTION

FIG. 1 is a top right rear perspective view of a headphone hanger;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and,

FIG. 8 is a top right front perspective view thereof.

All broken lines in the drawings illustrate portions of the headphone hanger that form no part of the claimed design.
